MULTI-STAGE LINT CLEANER

Hoyle G. Moss, Lubbock, Tex., assignor of one-fourth to Ennis E. Moss, Sr., one-fourth to Ennis E. Moss, Jr., and one-fourth to James P. Moss, all of Lubbock, Tex.

Application October 15, 1956, Serial No. 616,042

5 Claims. (Cl. 19—67)

This invention relates to lint cotton cleaners of the type in which the cotton in the form of a thin bat is progressively fed endwise into the peripheral path of a rapidly revolving toothed cylinder which pulls the fiber from the end of the bat and present circumferentially to cleaning instrumentalities, the cotton being removed from the toothed cylinder by suitable doffing means.

One of the objects of the invention is the provision of a lint cotton cleaner of the type described, in which a thin bat from a bat forming condenser passes between a set of drawing rolls on its way to the toothed cylinder, by which rolls it is drawn still thinner so that the edge of the bat presented to the cylinder is a thin fringe, resulting in each tooth of the cylinder catching only a few of the cotton fibers so that a very thorough cleaning of the lint is accomplished.

Another object of the invention is the provision of a double cleaner of the type described, in which the cotton is successively cleaned upon two toothed cylinders, the transfer from one to the other being effected by an intermediate transfer drum, the relative peripheral speeds of the cylinders being such that the cotton is combed adjacent the points of tangency of the cylinders with the transfer drum, whereby the fibers are brought into a relative position of parallelism.

Still another object of the invention is the use of air in precisely directed jets, for assisting in the transfer of the cotton from the first toothed cylinder to the transfer drum and from the transfer drum to the second toothed cylinder, the fibers being scoured by frictional contact with the jets as well as being arranged parallel.

A still further object of the invention is the control and inhibition of spurious and conflicting air currents generated by the rotation of the toothed cylinders and transfer drum, so as to prevent the fibers from being subjected to turbulence, which is a primary cause of nepping.

Other objects of the invention will appear as the following description of a practical embodiment thereof proceeds.

In the drawing which accompanies and forms a part of the following specification:

The sole figure is a side sectional view of a lint cotton cleaner embodying the principles of the invention, the section being taken in a vertical plane.

Since in the illustrative example the toothed cylinders are shown as saw cylinders, they will hereinafter in the specification be referred to as saw cylinders, but this does not rule out the eligibility of other types of toothed cylinders as equivalents in carrying out the purposes of the invention.

Referring now in detail to the drawing, the general casing 1 in the drawing, which encloses the working parts, and the side walls of which support the bearings for the rotatable parts, has an inlet opening 2 at the top, adapted to register with the discharge opening of a superposed bat forming condenser such as the conven-

2

tional type, in which the cotton collects on the exterior of a perforated cylinder evacuated on the inside, from which it is continuously scraped in the form of a thin coherent bat. The bat enters through the opening 2 into the cleaner, passing through successive pairs of drawing rolls 4 and 5, the lower pair rotating at a faster speed than the other pair, thus reducing the thickness of the bat. This necessitates that the rolls of the lower pair be more closely spaced than those of the upper pair to maintain frictional grip on the bat. Beneath the lower pair of drawing rolls is the feed roll 6, which in cooperation with the feed bar 7, presents the end of the bat to the saw cylinder 8. The thinning of the bat puts it in better condition to deliver it to the saw and at the same time has tendency to decrease the mattiness or lumpiness of the sample by stretching out the thin spots, giving a more uniform density in the bat thickness.

The feed bar 7 has a curved face 9 parallel to the adjacent arc of the feed roll, and narrowly spaced therefrom, through which space the thin bat is conducted by the feed roll. The end of the bat which is reduced to a mere fringe is continuously combed off by the teeth of the saw cylinder 8, the bat being subject to an abrupt direction change about the nose 10 of the feed bar, which prevents the saw teeth from tearing off lumps of cotton extending up into the space between the feed bar and feed roll, provided that the bat is held between said bar and roll with uniform frictional pressure across its entire width, which would be the normal condition except where the bat might be affected by thin places, where the frictional pressure would be relatively light. The saw cylinder 8 is preferably rotated at such speed that each tooth combs off only several fibers from the fringe of the bat, so that extremely thorough cleaning is accomplished.

The feed bar 7 has a flat face 11 adjacent the nose, which lies close to the periphery of the saw cylinder, its function being to seat the cotton positively into the saw teeth. Beyond the flat face 11 the feed bar has a face 12 divergent in a direction away from the saw, providing a space into which the fibers which are under restrained centrifugal force beneath the face 11 snap out as they pass the shoulder 12 at the end of the face 11. A considerable portion of the motes and trash are thrown off from the lint in this snapping movement, and the fibers stand out centrifugally in position to be impactively contacted by the grid bars 13.

Said grid bars form a series that encompasses the saw cylinder through an arc extending between the feed bar 7 and a partition 14 which divides the lower part of the casing 1, forming a trash chamber 15 to the left of said partition underlying the grid bars, which chamber converges downwardly to a mote and trash flue 15', which is maintained under suction. The cotton fibers stand out under centrifugal urge in the spaces between the grid bars and are knocked flat upon contacting the grid bars, giving up more of their trash through the inertia of the trash. The grid bars are spaced sufficiently close to keep the cotton traversing the spaces from rising to the extent that some of it might fly off and be lost with the trash.

In the statement of objects of the invention the detrimental effect was referred to, of spurious air currents creating turbulence within the cleaner. Such air currents are for the most part generated by the rotation of the saw cylinders and transfer drum, which are of relatively large diameter and driven at high speed. By way of illustration, it may be said that the saw cylinders may be twenty inches in diameter and the transfer drum sixteen inches, these dimensions of course, not being critical to the invention.

There is a narrow peripheral space between the sur-

face of the saw cylinder above which the teeth rise, and the outer boundary of the coating of cotton on the teeth from which the air is somewhat evacuated through centrifugal force, the coating of cotton tending to preserve the vacuum so that there is the continual urge of the saw cylinder to draw in air from wherever it can be found, to fill this vacuum. If air can be excluded from this peripheral space, such spurious currents are suppressed and turbulence within the chamber reduced to a minimum. The effect of turbulence is to impart uncoordinated or desultory movements to adjacent fibers, so that they tangle or knot or twist, becoming thereafter inseparable by any known means, and forming thick points or neps in the yarn and in the fabric woven therefrom.

Referring to the drawing, it will be noted that the part of the casing 1 which contains the drawing rolls and feed roll is substantially isolated by a back plate 16, forming part of the casing to the right of the drawing rolls, and that the lower end of said back plate is continuous with a curved shield 17 substantially concentric with the saw cylinder 8 through an extensive arc above and doffing station 18 and closely spaced with respect to the periphery of the saw cylinder. The lower end 19 of the shield 17 is deflected inwardly toward the saw cylinder so that it clears the teeth by a very small amount, for example, from one-sixteenth to one-eighth of an inch, whereby entry of air at the lower end of the shield is to a great extent prevented. However, as there is no cotton on the teeth in this section of the saw cylinder to act as a packing against the shield, some air will enter and discharge from the upper end of the shield. The part of the bat exposed between the pairs of drawing rolls is particularly vulnerable to eddy currents, so a flashing has been provided, consisting of a flexible plate 20 of rubber, for example, fixed to the back plate 16, and having its free end wiping against the feed roll 6. This flashing effectually prevents air currents which issue from the upper end of the shield 17 from reaching the region within the casing above said flashing and playing upon the exposed portion of the bat. The peripheral surface of the feed roll 6 is preferably spaced within one-sixteenth to one-eighth inch of the surface of the saw cylinder, so that any air current from the saw cylinder reaching the fringe of the bat is minimized.

At the doffing station 18, the saw cylinder 8 is tangent to a transfer drum 21, which in the illustrative example is also a saw cylinder with the teeth pointing in the same direction as those of the saw cylinder 8, the peripheries of the two cylinders traveling in the same direction in the region of tangency and the transfer drum rotating at the greater peripheral speed. Below the point of tangency, the saw cylinder 8 is provided with a pan or shield 22, which extends from a point adjacent the doffing station to a point adjacent the series of grid bars, and being designated from its proximity to the grid bars, as the grid pan. As shown, it is connected to the partition 14, but this is not vital. It lies close to the periphery of the saw cylinder 8 and is farther away at the partition end 23 than at the end adjacent the point of tangency of the saw cylinder and transfer drum.

Since the saw cylinder 8 is loaded with cotton throughout the arc covered by the grid pan, the cotton effectively packs the end 23 against entrance of air, while the movement of the cotton through the gradually increasing space creates a substantial vacuum within the grid pan. Said grid pan is provided with a flat face 25, extending downwardly from its end 24, which in conjunction with the adjacent side of the transfer drum 21 and also with the face 26 of a pan 27 that underlies the transfer drum, defines a nozzle capable of delivering a precisely directed jet of air to the cotton at the point of transfer. The rapid movement of the saw cylinder 8 extends the vacuous condition which permeates the cotton which coats the saw, upwardly beyond the end 24 so that the inducted air jet does not turn about the

end 24 and go down between the grid pan and saw cylinder, but advances straight forward, expanding into the space 33 between the saw cylinder and transfer drum, and assists in transferring the cotton from the teeth of the saw cylinder to the transfer drum by diminishing the pressure of the teeth against the cotton which they carry. Since the peripheral speeds of the saw cylinder and transfer drum are greater than the velocity of the air jet generated through their rotation, the effective movement of the air is downward frictionally against the lint, and tends to comb the fibers into parallelism. It will be readily understood that there would be an upward air flow in the space 33 and past the teeth of both saw cylinder and transfer drum at the point of tangency in the absence of the grid pan 22 and the nozzle defining faces 25 and 26, but the flow would be derived from the peripheral currents induced by the saw cylinder and transfer drum, which would come together at a conflicting angle, causing eddy currents and turbulence in the space 33, which it is the object of the present invention to suppress.

The purpose in having the shield 22 closer adjacent the partition 14 than adjacent the doffing point is that it has been found that the entering side of the shield should be spaced farther from the saw than the leaving side, in order for the air generated by the saw cylinder to be gradually suppressed and the cotton somewhat expanded so that it can be more or less opened by the impinging air jet from the nozzle at 25.

The transfer drum 21, in the form shown, is a saw cylinder rotating in a direction opposite to that of the saw cylinder 8, with the abrupt faces of the teeth leading, so as to strip the cotton from the saw cylinder 8. The transfer drum is the means for conveying the cotton from the saw cylinder 8, which with its associated cleaning instrumentalities, represents the first cleaning stage, to the saw cylinder 28 which with its correlated cleaning means, represents the second cleaning stage, the last mentioned saw cylinder having its teeth travelling in the same direction at the point of tangency as the teeth on the transfer drum, the latter teeth having their abrupt faces leading so as to strip the lint from the transfer drum. The saw cylinder 28 has a greater peripheral speed than the transfer drum.

A driven roll 29, which is preferably but not necessarily toothed, is mounted above the transfer drum 21 tangent thereto at the peak of the upper arc of its path of rotation, the purpose of which roll is to seat the cotton firmly in the teeth of the transfer drum. Between the roll 29 and the points of tangency of the transfer drum with both saw cylinders, are the arcuate shield plates 30 and 31. These are concentric with the transfer drum and lie close to the periphery thereof, and as the transfer drum is loaded with cotton in the arcs covered by these shields, there is a substantial exclusion of air currents travelling beneath them in a circumferential direction, and a vacuous atmosphere permeates the cotton coating, inducing a precisely directed air jet through the nozzle defined between the flat end flange 32 of the shield plate 30, and the roll 29. This air jet blows into the space 34, but since the transfer drum is necessarily travelling faster than any air movement that it can create, it follows that the lint cotton passes through the jet and in the direction thereof at the point of transfer, the fibers becoming arranged parallel in the same manner as has already been described with respect to the induced air jet at the space 33.

Such of the air that gets by the roll 29 at its point of tangency escapes through the space 35 between the roll 29 and the adjacent end of the shield plate 31. The projection 19 which has hereinbefore been referred to as restricting the entrance of air between the saw cylinder 8 and the shield 17, has another function, as a diverter to direct cotton which may not be firmly attached to the transfer drum, into the passage between the shield plate 30 and the doffing drum, where it will eventually become

firmly seated in the teeth of the transfer drum by the roll 29.

The transfer drum is underlain by a mote pan 36 of arcuate cross-section, having its opposite side edges approaching very close to the periphery of the transfer drum, so as to restrict the flow of air about the lower arc of the transfer drum, which is unloaded in this part of the path of rotation of the transfer drum, so as to maintain a vacuous climate in the space between said pan and drum. The mote pan catches the small trash which may have fallen out of the cotton onto the peripheral surface of the drum. At its lowermost point, the mote pan has a discharge opening 37, guarded by a driven vacuum valve 38, which prevents air from getting into the space between said mote pan and transfer drum while permitting the exit of the trash. The casing of the vacuum valve opens into a trash hopper 39, which underlies also the saw cylinder 28 and converges to the mouth of a suction duct 40.

The side of the mote pan 36 adjacent the region of tangency 41 between the transfer drum and saw cylinder 28 is formed as a cross bar 42 of triangular cross-section, seated in the divergent space formed between the adjacent peripheries of the transfer drum and saw cylinder, having the projecting end portion 43, which approaches close to the teeth of the transfer drum, and having a planiform face 44 close to the saw cylinder 28, the function of which is to set the cotton firmly in the teeth of the saw cylinder which was transferred to the saw cylinder at the region of tangency.

The saw cylinder 28 is associated with a series of grid bars 45, similar to the grid bars 13, and having the same function, said grid bars 45 being more closely spaced than the grid bars 13, since the peripheral speed of the saw cylinder 28 is greater than that of the saw cylinder 8 and there is greater need to shorten the interval between grid bars in which the cotton is free, so that it will not have time to fly out centrifugally to its fullest extent, which would cause some of it to slip off of the teeth and be lost with the removed trash that falls into the underlying hopper 39.

The transfer drum 21 is loaded with cotton when it passes beneath the shield plate 31, so that a vacuous condition is maintained beneath said plate. The saw cylinder 28 is provided with a top shield 46 overlying the upper arc of its path of rotation, being substantially concentric with said saw cylinder and lying almost contiguous to the teeth of said cylinder. While the teeth of the saw cylinder are empty when travelling beneath this shield, the restriction of the space inhibits any substantial passage of air through the space, induced by the rotation of the saw cylinder. The vacuous condition in the cotton passing beneath the shield plate 31 induces a precisely directed air jet into the space 47 through the nozzle defined between the leading end 48 of the shield plate 31 and the adjacent part of the saw cylinder, and the flange 49 at the adjacent end of the top shield 46. Through the presence of the shield plate 31 and top shield 46, all air currents which would conflict with the air jet are suppressed; there is no turbulence in the space 47, and the cotton is combed in an orderly manner by the air jet, and the fibers arranged parallel in the same manner as described with reference to the air jet which functions at the transfer point between the saw cylinder 8 and the transfer drum.

The description now shifts to the doffer 50, which removes the cleaned lint from the saw cylinder 28 and delivers it to the lint flue 51. The doffer is of the conventional brush type, being a cylinder with parallel longitudinal rows of brushes extending radially about the drum. The doffer operates in a chamber 56, defined between an overlying part 52 of the casing and an underlying shield 53. Said chamber communicates with the lint flue 51 and has an atmospheric inlet 54 near the

top, the air from which normally blows downward toward the lint flue.

The doffer rotates at a faster peripheral speed than the saw cylinder 28, the rows of brushes moving substantially contiguous to the toothed surface of said saw cylinder at their point of tangency 55, most of the lint being thrown off by centrifugal force into the chamber 56, and being swept into the lint flue by the air flow from the inlet 54 to the lint flue.

It is just as important that the cotton at the doffing point 55 be protected from turbulence caused by conflicting air currents, as at the other points of cotton transfer, so the side edges of the doffer shield 53 are made to approach to a position substantially contiguous to the path of rotation of the free ends of the brushes. At the left side the shield 53 has a flat flange 57, the outer side of which participates with other structure in forming a nozzle, as will appear. At the right, the side of the shield comprises an adjustable radially disposed plate 58. There is very little air in the pockets between the rows of brushes, most of it having been centrifugally expelled so that as these pockets pass the plate 58, very little air is brought into the space between the doffer and the doffer shield, and the purpose of the shield is to prevent any air being entrained or otherwise introduced to satisfy the vacuum. There is consequently suction at the point 59 where the doffer emerges from the adjacent restricted end of the space within the doffer shield. The plate 58 is made adjustable so that it may be moved sufficiently within the path of rotation of the brushes to assure against the entrainment of air which might divert into the space within the doffer shield some of the lint destined for the lint flue. The doffer shield, therefore, suppresses any circumferential air flow toward the doffing point, and also conserves the vacuum, effective to induce a direction controlled air jet, aimed at the point of transfer of the saw cylinder 28 and doffer 50.

The saw cylinder 28 is provided with an associated grid pan 60 between the series of grid bars 45 and the doffing point 55, which grid pan lies close to the teeth of said saw cylinder and like the grid pan 22, associated with the saw cylinder 8 which lies farther from the periphery of the saw cylinder at its mouth end 61 than at its heel. The saw cylinder is loaded when it passes this grid pan, so that the circumferential current of air set up by the frictional drag of the cotton coated toothed surface is effectively suppressed before it reaches the doffing point 55.

The forward end of the grid pan 60 is formed with a flat flange 62, which in coordination with the flat outer side of the flange 57 and the flat side 63 of the triangular cross bar 64, forms a nozzle directing an air jet to the doffing point 55, said air jet being unaffected by any currents, and lacking turbulence. This jet expands in the cotton adjacent the doffing point, assisting in its transfer to the doffer 50 and without increasing its liability of neppling, at this point. The grid pan 60, as shown, is continuous with the wall 65 of the trash hopper 39, so that the chamber of the casing from which the air jet to the doffing point 55 is drawn is separated from the hopper and free from contaminating particles.

The cotton removed by the doffer 50 follows around the doffer and then into the lint flue 51. It is the doffer which by its rotation produces the air flow for conveying the cotton to the lint flue, which air flow is boosted by the air that enters through the air inlet 54. There is a specific advantage in having said air inlet at a point above the doffer and over the lint flue. If for one reason or another the air duct which presumably leads to a battery condenser, not shown, becomes plugged up so as temporarily to block the flow of cotton into the lint flue, the cotton would, in the absence of the air inlet opening 54, back up in the chamber 56 so as to push itself around over the doffer to the doffing point and load the teeth of the saw cylinder 28 with the backed-up cotton. However, in the present invention, this will not happen. As soon

as the air inlet 51 becomes choked, the action of the doffer is to take in more air at the nozzle formed at 62, to satisfy the actual need of the doffing operation. Consequently, as this air has no place to go except to the inlet opening 54, it chooses this path and carries the cotton outside of the machine to a suitable bin, not shown, provided to receive it. The above refers, of course, to an emergency functioning of the apparatus.

While I have in the above description disclosed a practical embodiment of the invention, it will be understood by those skilled in the art that the specific details of construction and arrangement of parts are by way of example and not to be construed as limiting the scope of the invention.

What I claim is:

1. Apparatus for cleaning lint cotton in successive stages comprising, a first stage saw cylinder, means for progressively presenting cotton in bat form, endwise to said first stage saw cylinder, a second stage saw cylinder, means for doffing the cleaned lint from said second stage saw cylinder, a transfer cylinder between said saw cylinders tangent to both, receiving cotton from said first stage saw cylinder and transferring it to said second stage saw cylinder, at the respective points of tangency, means operatively related to adjacent cylinders at each point of tangency, at the sides of said respective points of tangency approached by the cotton laden portions of said first stage saw cylinder and said transfer cylinder for inhibiting convergent air currents travelling circumferentially of said adjacent cylinders, and forming nozzle passages for directing air jets toward said respective points of tangency, a roll tangent to said transfer cylinder at an intermediate point in the cotton laden arc of its path of rotation for setting the cotton on said transfer cylinder, and a shield closely embracing said transfer cylinder through an arc extending from a point adjacent the retreat side of the point of tangency between said first stage saw cylinder and said transfer cylinder, to a point adjacent said roll, said shield being spaced from said roll to permit entrance of air to the point of tangency of said roll with said transfer cylinder, induced by rotation of said roll, for paralleling the fibers outstanding from said transfer cylinder.

2. Apparatus for cleaning lint cotton in successive stages, as claimed in claim 1, the transfer cylinder being toothed.

3. Apparatus for cleaning lint cotton in successive stages comprising a first stage saw cylinder and means for feeding cotton thereto, a second stage saw cylinder, a doffer for removing the lint from the second stage saw cylinder, and a transfer cylinder between said first and second stage saw cylinders tangent to both, receiving cotton from the first stage saw cylinder and transferring it to said second stage saw cylinder, a series of spaced grid bars in operative proximity to said first stage saw cylinder, beyond said feeding means and a similar series of spaced grid bars operatively related to the second stage saw cylinder beyond the transfer point of cotton to said second stage saw cylinder, a shield pan underlying said transfer cylinder having its edges in close relation to the periphery of said transfer cylinder for suppressing air flow circumferentially of said transfer cylinder and maintaining a vacuous atmosphere between said shield pan and the part of the transfer cylinder carried thereby, said shield pan being a collector for loose trash dropped from the cotton onto the surface of said transfer cylinder, said shield pan having a trash discharge opening, a vacuum retaining gate valve controlling said opening for discharging the trash into trash disposal means, a grid shield closely embracing a cotton laden portion of said first stage saw cylinder between the associated series of grid bars and the point of tangency between said first stage saw cylinder and said transfer cylinder, said grid shield cooperating with the adjacent end of said shield pan to form a nozzle passage to direct an air jet to said point of tangency, said grid shield being instrumental in creating a

vacuum in the cotton passing said shield which draws an air jet through said nozzle passage.

4. In a cleaner for lint cotton, a casing housing the elements hereinafter defined, a toothed cylinder to which cotton is fed and a doffer cylinder with spaced rows of brushes tangent to said toothed cylinder, a series of spaced grid bars in operative proximity to said toothed cylinder beyond the feeding point, a grid shield closely embracing a cotton laden portion of said toothed cylinder beyond said series of grid bars, a doffer shield underlying said doffer cylinder having its end which is adjacent said grid shield substantially contiguous to the path of travel of the ends of said brushes, for suppressing circumferential air flow through the space underlain by said doffer shield, the latter cooperating with said grid shield to form a nozzle passage for directing an air jet toward the point of transfer between said toothed cylinder and said doffer cylinder, said grid shield being instrumental in creating a vacuum in the cotton passing said shield, which vacuum draws an air jet through said nozzle passage, a lint flue opening into said casing adjacent the end of said doffer shield remote from said nozzle passage and below said doffer, an air inlet opening into said casing over said lint flue for directing an entering air flow toward said lint flue, and an adjustable plate at the said remote end of said doffer shield settable to substantially inhibit the entrance of air into the space covered by said doffer shield and to prevent the vacuum maintained in said space from diverting lint from said lint flue.

5. Apparatus for cleaning lint cotton in successive stages comprising, a first stage saw cylinder, means for progressively presenting cotton in bat form endwise to said first stage saw cylinder, a second stage saw cylinder, means for doffing the cleaned lint from said second stage saw cylinder, a transfer cylinder between said saw cylinders tangent to both, receiving cotton from the first stage saw cylinder and transferring it to the second stage saw cylinder, at the respective points of tangency, pairs of adjacent arcuate shields closely embracing the arcs of adjacent cylinders at each point of tangency, at the sides of said respective points of tangency approached by the cotton laden arcuate portions of said first stage saw cylinder and said transfer cylinder, for inhibiting convergent air currents travelling circumferentially of said cylinders, the shields of each pair being separated at their adjacent ends, forming nozzle passages for directing air jets to the corresponding points of tangency, the respective shield of each pair which embraces the cotton laden portion of the corresponding first stage and transfer cylinders, producing a vacuum in the confined cotton effective beyond the ends of said shields proximate the corresponding points of tangency, to induce an air jet through the corresponding nozzle passages to comb the cotton and assist in its transfer, a roll tangent to said transfer cylinder at an intermediate point in the cotton laden arc of its path of rotation for setting the cotton on said transfer cylinder, and a shield closely embracing said transfer cylinder through an arc extending from a point adjacent the retreat side of the point of tangency between the first stage saw cylinder and transfer cylinder to a point adjacent said roll, said shield being spaced from said roll to permit the entrance of air to the point of tangency of said roll with the transfer cylinder, induced by rotation of said roll, for paralleling the fibers outstanding from said transfer cylinder.
